UNITED STATES PATENT OFFICE

CHRISTIAN WILHEJELM, OF PHILADELPHIA, PENNSYLVANIA

TEMPERATURE-CONTROL APPARATUS

Application filed June 26, 1929. Serial No. 373,741.

My invention relates to improvements in temperature control apparatus adapted for use in connection with a furnace which is heated by oil or gas, the admittance or supply of which is controlled by one or more valves.

The object of my invention is to provide an apparatus having certain novel features of construction and operation whereby an overshooting of the temperature is prevented, particularly during the heating up period, and whereby an almost perfect control is assured while the furnace operates at its predetermined operating temperature.

15 My invention includes other more or less important features, all having as their object and function the provision of an automatic temperature control apparatus adapted for use under the many varying conditions of modern furnace practice. I prefer, however, to explain the apparatus in detail before elaborating or commenting upon the advantages and objects of my invention to a greater extent than hereinabove, so much 20 more so, as the apparatus is of a somewhat complicated nature.

Referring therefore to the accompanying drawing which is a wiring diagram the reference numeral 1 denotes a furnace which is heated by fuel supplied through a pipe 2 controlled by a valve 3. A thermostat 25 of commercial type is mounted in the furnace wall and responds to temperature changes within the furnace. The thermostat may consist of an expansible metal rod 4 which is mechanically connected at 5 to a metal tube 6 having a different co-efficient of expansion than the rod.

The tube is fixed in the thermostat frame 40 7 which is mounted immovably in any usual manner. The rod is provided with a rack 8 for operating a gear 9 on the indicator shaft 10 which carries a pointer 11 for indicating temperature changes on a scale 12.

45 The indicator shaft 10 carries three non-conducting cams 13, 14 and 15 adapted to close respectively three pairs of contacts 16, 17 and 18. Each pair comprises a fixed contact and a movable contact which latter is actuated by the adjacent disk in an obvious

manner. The arms are conveniently mounted on a base 19 from which depends a support 20. On the latter is pivoted at 21 a fibre cam 22 adapted to operate two pivoted conducting contact arms 23 and 24 with respect to two fixed contacts 25 and 26.

At the top of the cam 22 there is pivoted at 27 a substantially T-shaped finger 28 having an armature 29 adapted to be attracted by an electromagnet 30. The finger 28 is 60 extended upwards and carries a button 31 which is kept in frictional contact with the disk 13 by spring 32 between the finger 28 and the cam 22. The two latter elements are thus mounted to oscillate together on the pivot 21, 65 and in addition the finger may oscillate on the pivot 27 towards and away from the cam 22 and the magnet 30.

The complete mechanical construction of all of the above described parts is not shown 70 because they may be varied as desired so long as the several parts are arranged to function as hereinafter set forth.

The contacts 17 and 18 control the circuits through two relays which comprises a relay 75 coil 33 having a non-conducting armature carrying a top and a bottom conducting bar 34 and 35 respectively, and a second relay coil 36 having a non-conducting armature also carrying a top and bottom conducting bar 80 37 and 38 respectively.

The armatures are normally in lowered positions as shown, in which case the bottom bars 35 and 38 serve to bridge contacts 39-40 and 41-42 respectively. When the relay 85 coils are energized, the armatures are lifted and the top bars 34 and 37 then bridge contacts 43-44 and 45-46 respectively.

The numeral 48 denotes a motor which drives a timing cam 49 adapted to open and close certain circuits through two pairs of contacts 51 and 52 respectively, suitably mounted on fixed bases.

The reference numeral 55 denotes a reversible electric motor which rotates a crank 95 disk 56. To the latter there is pivoted a link 57 which is pivotally connected at 58 to a valve operating lever 59 which in turn is pivoted on an adjustable floating pivot 60 carried by a base arm 61. The free end of 100

the lever 59 is connected to the valve 3 by a link 62. One end of the base arm 61 is pivoted at 63 underneath the lever 59. The other end of the base arm is pivoted on a nut 64 threaded on an endless screw shaft 65 suitably driven by a second reversible motor 66 by way of a reducing gearing 67 and an interposed timing clutch mechanism which comprises the following elements.

10 The screw shaft 65 carries a gear 101 which meshes with another gear 102 on another screw threaded shaft 103. The latter has threaded thereon a pinion 104 which meshes with a wide gear 105 on a shaft 106 driven from the motor 66. The pinion 104 carries two clutch members 107 and 108. The shaft 103 carries two other clutch members 109 and 110, mounted to rotate with the shaft. The parts are so arranged that when the gear 105 rotates, it will in turn rotate the pinion 104 and the latter with the two clutch members 107 and 108 will travel on the screw threaded shaft 103 without rotating the latter.

15 Eventually, however, either of the members 107 or 108 will reach and engage either of the clutch members 109 or 110, respectively. When this occurs, either of the latter and the shaft 103 will be rotated and through 20 the gears 102 and 101 will rotate the shaft 65.

25 The members 109 and 110 are adjustably carried by the shaft 103 in any well known manner as by locknuts for instance, not shown, consequently the period elapsing between the time when the pinion 104 starts to rotate and until the shaft 103 is rotated, may be adjusted and regulated because the distances between the clutch members 107 and 109 on the one side, and between the 30 clutch members 108 and 110 on the other side are adjustable by moving the members 109 and 110 along the shaft 103.

35 The arm 61 has pivoted thereto a link 68 which operates a bell crank 69 in a limit switch comprising two pivoted conducting contact arms 70 and 71 and two fixed contacts 72 and 73. The link 57, operated from the first reversible motor 55, also operates a bell rank 74 in another limit switch which 40 comprises two pivoted conducting contact arms 75 and 76, and two fixed contacts 77 and 78. The bell crank 74 also carries a pin 79 which operates an arm 80 pivoted at 81 and which arm carries a flapper contact 82.

45 The drawing shows the parts in their positions while the furnace is running at its operating temperature. At this time the valve is in a position half way between the open and closed position of its initial stroke. That 50 is to say, in order to maintain the operating temperature in the furnace the valve must necessarily be open to an extent where the fuel supply balances the fuel demand.

55 However, before reaching this operating position, the valve has had an initial move-

ment from its closed position to an extent greater than required for operating purposes, or the furnace would never heat up, or only very slowly. Therefore, when the temperature is near the operating or control point as it is called, the valve is moved back to a 70 half way position or the temperature would overshoot.

Again, it would be understood that the half way position is not between fully open and fully closed, but half way between the limits either way within a zone suitable for regulating the particular furnace at whatever work is performed.

60 During the undisturbed operation of the furnace, it will be seen, that there is no current passing through the apparatus, except that the timing motor cam 49 is periodically closing a circuit from the line, through wire 100, contacts 51 to the magnet 30 and out. Consequently the magnet is energized periodically to attract armature 29 on finger 28, but this movement which is in the nature of a click or snap does not accomplish anything at this time.

65 Let us assume, however, that for some reason the temperature decreases. The rod 4 will then contact and turn the shaft 10 and the disks clockwise and contacts 17 will close and establish a circuit as follows.

70 From the line, to wire 90, to 17, to wire 91, to contacts 23—25, wire 92 to relay 36 and out. The relay will be energized and pull up its armature, hence a motor circuit will be established as follows. From the line 100 to contact bar 37, contact 46, to wire 93, to contacts 77—75 to the initial motor 55 and out through wire 94.

75 The motor 55 will start and operate crank disk 56 anticlockwise and give the valve 3 a quick initial opening movement through the parts 57—59 and 62, the arm 59 moving to the left on pivot 60. At the same time, however, the link 57 will also operate bell crank 74 until it engages contact arm 75 110 and breaks the motor circuit at 77. When this happens the arm 80 will have been moved on pivot 81 by the pin 79 so that flapper contact 82 now touches contact 78 and the motor 55 stops.

80 In nearly all cases, this movement of the valve will be sufficient to admit enough additional fuel to check the drop in temperature and in actual practice, the temperature line on the usual recording graph shows hardly any deviation from a straight line and the temperature will go back to normal.

85 Now it will be seen that when the disks turn clockwise, the button 31 is moved to the left, hence the finger 28 and cam 22 move anticlockwise on the pivot 21, but the contact at 23—25 remains closed and the relay 125 remains energized. As the temperature now returns to normal, contacts 17 are again 130

opened, the relay 36 circuit is broken and the armature falls down thereby breaking the motor circuit at 37-46.

The dropping of the armature, however, 5 closes a motor circuit from the line through lower relay contacts 42-41-40-39 to wire 99 to flapper contact 82, to 78-76 to the initial motor 55 and out. Consequently the motor operates in the opposite direction and 10 moves (closes) the valve back to a new normal position, because the closing movement is of lesser extent than the opening movement in that flapper contact 82 makes a quick break but has a slow closing movement as is 15 obvious.

However, let us consider that the drop in temperature is greater than that assumed above. In that event contacts 16 will also be closed and a second motor circuit will be 20 closed from the line to 37-45, wire 96, 73-71, to balancing motor 66 and return through wire 97, contacts 16 and back to the line.

In this event, the two motors start running 25 practically at once, but the balancing motor does not move the valve immediately, there being a time lag interposed until the clutch member on the pinion 104 reaches the clutch member 110 on the shaft 103 as explained 30 above.

The balancing motor 66, will now start and operate the endless screw 65 to move pivot 64 and lever 61 to the right on pivot 63, hence also move pivot 60 to the right and 35 thus swing the arm 59 to the left around pivot 58 and thereby cause a still further opening of the valve. The balancing motor will also through the link 68 gradually move bell crank 69 towards the arm 71 and if the 40 movement of the motor 66 is permitted to continue, the arm 71 will eventually be swung away from 73 and the balancing motor circuit will be broken. When this happens, the valve will be fully open.

In nearly all cases it is not necessary nor 45 desirable to continue the operation of the balancing motor until the valve is fully opened because to do so will cause a violent rise in the temperature which may cause 50 overshooting. Therefore, the apparatus is designed so that the balancing motor is stopped as soon as the temperature rises towards the control point and the initial motor is operated to cause a closing movement of 55 the valve in order to prevent a too great rise of the temperature caused by the operation of the balancing motor, which is always set to cause a quick correction.

These two operations are accomplished as 60 follows. The temperature will have commenced to rise because of the partial opening of the valve. The thermostat rod 4 will therefore commence to expand and move the disks 13, 14 and 15 slightly anticlockwise. 65 This movement, however, includes a clock-

wise movement, to the right in the drawing, of the friction button 31 and finger 28 on the pivot 21. Consequently the cam 22 will also move clockwise and break the circuit through relay 36 at 25 in the anticipator 70 switch mechanism. The connection between 23 and 25 will therefore remain broken so long as the temperature keeps going up. As a result, the relay armature 38 will drop and the balancing motor circuit will be 75 broken at 45 and further opening movement of the valve ceases.

At the same time, when the relay 36 is de-energized the circuit mentioned above is established through lower relay contacts to 80 wire 99 to flapper contact 82—which had been moved into engagement with contact 78—to contacts 78 and 76 to the initial motor 55 and out through wire 94.

The closing of this last mentioned circuit 85 moves initial motor 55 in the direction opposite to its initial movement and causes a closing movement of the valve to anticipate and check a too great fuel supply as above explained. The circuit is broken when the bell 90 crank 74 moves flapper contact arm to break the circuit at 78 and the motor 55 stops.

It should again be noted, however, that the valve is at this time not moved back or closed to its former position, because, before the 95 first closing movement of the valve occurs, it has received first an initial opening movement and secondly a further balancing opening movement. Therefore, when the initial motor now operates to close the valve, this 100 closing movement is necessarily of a lesser extent because the flapper contact 82 snaps away from the contact 78 in less time than it takes to move 82 over into engagement with 78.

At this time, therefore, the normal position of the valve while the furnace operates at desired predetermined temperature is half way between fully open and fully closed position so that when a change in temperature occurs, the initial stroke of valve will cause it to be shifted to a new normal position in order that the correct quantity of fuel may be supplied in response to the changed demand.

We have now turned the corner and the temperature is on the increase back to normal, and continuing the description, it will be seen that if the temperature continues to rise there will be no further shifting of the valve 110 by the balancing motor, but there will be one or more operations of the initial motor because, although the temperature keeps going up we do not know whether it will ever reach the normal operating control point and it is therefore necessary to do two things.

First the valve must be opened again to insure additional fuel supply so that the control point temperature may be reached within the time necessary or desirable for that 130

particular furnace job. Secondly, the valve openings and closings must be taken care of in time to insure that the temperature does not go beyond the control point.

5 These two objects are accomplished by means of the timing cam 49 working together with the anticipator switch, it being remembered also that while the temperature keeps going up, the thermostat rod 4 keeps on expanding and the disks on the shaft 10 keeps turning slowly anti-clockwise, consequently the cam 22 is swung to the left in the drawing and the relay 36 circuit remains open at 23-25 as aforesaid.

15 The cam 49 is arranged to make one revolution during each time lag period of the furnace, i. e. the time which elapses before the temperature reacts in response to a change in the fuel supply.

20 At the end of each time lag period, therefore, the cam 49 will close contacts 51 to establish a circuit through the magnet 30 and back. The magnet will be energized, attract armature 29 and finger 28 on the pivot 27 25 against the tension of spring 32, thereby releasing the frictional contact between the button 31 and disk 13.

This release lasts for about one or two seconds only after which the magnet 30 is de- 30 energized because the contacts 51 will open as soon as the cam 49 passes by them. Therefore the spring 32 will again pull the button 31 into contact with the disk 13. During the momentary release of the button 31 and 35 finger 38, the spring 50 will however move arm 23 to engage contact 25 to again momentarily close the initial relay circuit through relay 36 to motor 55. The valve will therefore again receive an opening movement until 40 the initial motor circuit is again broken at 77 as above described, and flapper contact 82 will again engage contact 78. This opening movement is however very slight and may be adjustably delayed by adjusting the contacts 45 in arm 25 as shown.

If now the temperature continues to rise during the next succeeding time lag period and before the cam 49 closes contacts 52, the continuing anti-clockwise movement of the 50 disk 13 will again move the finger 28, as before, to break the relay 36 circuit at 23-25. The armature will drop and again establishing a circuit via 42-41-40-39-99-82-78-76 to initial motor and cause a movement 55 on the part of the initial motor 55 to close the valve. When now the interruptor 49 closes contacts 52, nothing will happen to the motors because both relays are down.

If, however, the rise in temperature is too 60 slow or stops or even tends to drop again, then the cam 48 will through contacts 52 close a circuit to the balancing motor 66 via wire 120 and start the motor to cause an additional movement of the valve.

65 This movement, however, will be stopped

as soon as the drop in temperature has been arrested, because now the disks will again turn anticlockwise to swing the finger 28 and cam 22 to the left to break the relay 36 circuit at 23-25 and the motors stop. The latter are now operated back into their normal position because of the initial motor circuit through the lower relay contacts and because of the circuit to the balancing motor 66 through contacts 52 and wire 120 which operates the balancing motor in the opposite direction.

70 From the foregoing it will be clear that when the temperature drops, the motors will be operated to open the valve to admit more fuel. But when the drop has been checked and the temperature goes back to the control point, the operations of the motors are governed by the mechanisms which include the anticipator switch and the timing cam.

75 The anticipator switch seeks to break the motor-relay circuits ahead of the time when the valve should be closed while the temperature goes up. The timing cam closes the motor-relay circuits immediately after they are broken if the break occurs too soon within a time lag period, because in the latter event, the valve should not be closed but should be opened.

80 This is the main distinguishing feature of my invention. It will be seen that contrary to usual practice, which closes the valve when the temperature goes back to normal, this invention provides mechanism which opens the valve in order to anticipate a lag in the 100 rise, and which mechanism so operates the motors that even a large opening movement may be obtained.

85 On the other hand, due to the timing feature, the valve is prevented from opening more than necessary and the valve is so regulated that it is back in a new normal position, half way between the limits of its new initial stroke corresponding to the new fuel demand required by the changed condition 110 in the furnace. This has in and of itself nothing to do with the temperature, the changes in which are merely the result of the new conditions, because it will readily be seen that with a heavy load a furnace requires more fuel for a given temperature than with a less heavy load. Therefore, an apparatus which merely varies the fuel supply in proportion to the change in temperature and at a corresponding rate is not satisfactory.

115 We can now briefly consider the operation when the temperature increases from normal. At this time the disk will turn anti-clockwise and relay 33 will be energized via 90-18-24-26 and wire 115. The armature of the relay will be pulled up and current will pass from the line to 34-43 and wire 116-78-76 to initial motor 55 starting the latter to actuate the valve mechanism to close the 130

valve, and the initial motor circuit will then at this time be broken at 76-78 and flapper contact 82 will engage contact 77. Also, the balancing motor circuit will be closed from the line to 34-44 and wire 117-72-70 to cause the balancing motor to give the valve an additional closing movement. Finally we will have the same circuit as before from the line to flapper contact 82 to 77 and 75 to start the initial motor to open the valve, all in the 10 reverse direction to that described above.

However, as the temperature now is going down due to the decreased fuel supply, the valve having been operated to close, the disks will again turn clockwise, cam 22 will break 15 the relay 33 circuit at 24-26, the relay drops out and no further movement of the valve will be made by the motors.

The cam 48 however, will again function to reset the finger 28 to momentarily close 20 the relay 33 circuit at 24-26 to operate the initial motor 55 first to close and then to open the valve until the control point is reached. When the rise has been checked, and the temperature starts to drop back to 25 normal, the anticipator switch will operate as before, and if the movement back to normal is too fast so that there is danger of overshooting, the timing cam 48 will again operate to reset the finger 28 and operate the 30 balancing motor to close the valve.

The foregoing is thought to clearly explain the invention and its operation if the temperature varies plus or minus. The apparatus however, has also superior advantages during the heating up period.

At room temperature the thermostat is contracted and the disks 13, 13 and 15 will be in a position in which the two pairs of contacts 16 and 17 are closed while contacts 18 are 40 open. These room temperature positions are not shown. When then the main supply line is closed, the initial motor is started as before and also the balancing motor. The latter, however, is stopped to prevent a too violent rise and the initial motor is operated back to its half way position, all as explained above, when the apparatus operated to check a drop in temperature.

If the temperature continues to rise without additional fuel there will be no further shifting of the valve by the balancing motor.

What will happen if temperature continues to climb is:—That for every revolution of the time lag cam 48, magnet 30 will be energized and release friction button 31 from the contact disks for a second or so, and while being de-energized coil 30 will again allow 55 31 to drop back on disk 13.

While suspended in the air the spring 50 will force the contacts 23-25 together and bring button 31 back to a center position. Closing of contact 23-25 will energize relay coil 36 and send current from 46, 77-75 to opening field on initial motor 55 and the 60 valve will open from normal, break contact

at 77 and stop after flapper contact 82 has swung in contact with 78.

If now the temperature goes up in the following lag period before time lag cam 48 closes contacts 52 it is obvious that the movement of disk 13 in response to the temperature will thru finger 28 break the circuit at 23-25 for relay coil 36 and as explained before this will result in a movement back to normal by the initial motor and when time lag cam 49 closes contact 52 there will be no motion of the balancing motor 66 as both relays 33 and 36 are de-energized.

It is evident that so long as the temperature moves up towards the control point the action explained above will continue to repeat itself in each time lag period. If however the temperature remains unchanged or shows a tendency to drop, the action of disk 13 on arm 31 does not effect a break of contact 23-25 and the relay 36 remains closed causing the initial motor 55 to go back to open and the interruptor to cause motor 66 to operate to further open the valve. As soon as the temperature again increases, the anticipator breaks the circuit at 23-25. Relay 36 falls out and the initial motor goes back to normal and thus checks the movement of the temperature at the same time as no further movement of the balancing motor takes place unless the temperature goes down or ceases to go up.

It is evident that this arrangement will cause the valve only to be opened exactly the amount required as the temperature goes up. The reverse action takes place when the temperature goes high. This feature is absolutely essential on temperature control jobs where the fluctuations are very great due to very great and sudden load changes. It is also essential where a furnace is started from cold and where the control is expected to allow the temperature to raise to a certain point and then hold the temperature at that temperature without materially overshooting this point.

This control system as described will function as follows when furnace heats up. It will open the valve in order to bring the temperature up to the desired point. If the temperature begins to rise, the opening of the valve is stopped and counteracted to prevent a too rapid rise. If however the rise appears to be too slow, the valve will be further opened to insure the rapidity of rise desired.

When the temperature is outside a small zone 5° or 10° on either side of the control point, the valve is moved quickly while the temperature has a tendency to move away from the control point.

When the temperature is inside of the small zone, only slight corrections are necessary to the valve to bring the temperature to the control point. The anticipator device in normal practice does not interfere with the valve

movements while the temperature is maintained within narrow limits.

While the invention has been described as functioning to control the operations of a fuel supply valve to a furnace, it will readily be seen that the apparatus may with slight modifications be adapted to control electric heating system, pressures and other physical or chemical conditions.

10 I therefore reserve the right to make such changes or alterations as readily suggest themselves to a person skilled in the art for the purpose of adapting the invention to control conditions other than that described herein.

I claim:

1. The combination of a furnace having a fuel supply controlled by a valve for maintaining a predetermined temperature within the furnace, means for opening said valve to increase the fuel supply in the event the temperature decreases, mechanism for prematurely closing the valve when the temperature thereafter begins to increase and means for opening the valve during said increase if the said premature closing of the valve occurs within the time lag period of the furnace.

2. The combination of a furnace having a fuel supply controlled by a valve for maintaining a predetermined temperature within the furnace, means for closing the valve to decrease the fuel supply in the event the temperature increases, mechanism for prematurely opening the valve when the temperature thereafter begins to decrease and means for closing the valve if the said premature opening of the valve occurs within a time lag period of the furnace.

3. The combination of a furnace having a fuel supply controlled by a valve for maintaining a predetermined temperature within the furnace, means for opening said valve to increase the fuel supply in the event the temperature decreases, means for closing the valve when the temperature again begins to increase and means for prematurely opening the valve to anticipate a temperature lag while the temperature rises toward the said predetermined temperature.

4. The combination of a furnace having a fuel supply controlled by a valve for maintaining a predetermined temperature within the furnace, means for closing said valve to decrease the fuel supply in the event the temperature increases, means for opening the valve when the temperature again begins to decrease and means for prematurely closing the valve to anticipate a temperature lag while the temperature decreases towards the said predetermined temperature.

5. The combination of a furnace having a fuel supply controlled by a valve for maintaining a predetermined temperature within the furnace, means for operating said valve to vary the fuel supply in the event the tem-

perature changes within the furnace, means for operating said valve in a direction opposite to the direction of its first said operation when the change in the temperature has been checked and means for prematurely operating the valve in the said first named direction to anticipate a temperature lag when the temperature moves towards the said predetermined temperature.

6. The combination of a furnace having a fuel supply controlled by a valve for maintaining a predetermined temperature within the furnace, means for operating the valve to vary the fuel supply in response to temperature changes within the furnace, means for automatically operating said valve to check the variation in the fuel supply when the said temperature change has been checked and the temperature returns to the predetermined temperature, a device tending to prematurely operation of the valve to again vary the fuel supply to anticipate a lag in the said return of the temperature and means neutralizing the operations of said device if they tend to operate the valve within a time lag period of the furnace after the said changes in temperature have been checked.
